(57) **CLAIM**

The ornamental design for a mobile ECG sensor, as shown and described.

DESCRIPTION

FIG. 1 is a perspective view of a mobile ECG sensor; FIG. 2 is a front view thereof;

FIG. 3 is a top view thereof;

FIG. 4 is an end view thereof; and,

FIG. 5 is a bottom view thereof.

The broken lines shown in FIGS. 1 and 3 represent an environment and form no part of the claimed design.
